SANDING HEAD

William H. Hill and Hermon Clyde Hall,
Bassett, Va.

Application July 27, 1939, Serial No. 286,920

2 Claims. (CL. 51—191)

Our invention relates to abrasive implements and more particularly to improvements in sanding heads of the rotary multiple flap type.

The invention is designed with the particular purpose in view of providing a device of this type equipped for the storage therein of replenishing supplies for a plurality of sanding flaps readily accessible from the outside of the head for replenishing purposes and which is inexpensive to manufacture, reliable and efficient in operation, and adapted for easy attachment to a power driven shaft.

To the accomplishment of the above, and subordinate objects presently appearing, a preferred embodiment of the invention has been illustrated in the accompanying drawings, set forth in detail in the succeeding description, and defined in the claims appended hereto.

In said drawings—

Figure 1 is a view in side elevation of the preferred embodiment of the invention with the cover plate removed,

Figure 2 is a view in side elevation looking at the reverse side of the device,

Figure 3 is a view in transverse section taken on the line 3—3 of Figure 1 looking in the direction indicated by the arrows,

Figure 4 is a view in top plan,

Figure 5 is a view in side elevation of one of the roll holders, and

Figure 6 is a fragmentary view in transverse section taken on the line 6—6 of Figure 1 looking in the direction indicated by the arrows.

Describing the invention in detail, with reference to the drawings by numerals, the basic element of the sanding head is a cylindrical casing 1 of suitable metal open at one side and having a closed opposite side 2, and an axial inwardly extending hub 3 integral with the closed side 2. The casing 1 is adapted to be closed by a circular cover plate 4 of the same diameter as said casing and which is provided with an axial bore 5 therein of the same diameter as the bore 6 of the hub 3. The casing 1 and cover plate 4 are designed to be mounted on one end of a suitable power driven mandrel, represented by dotted lines at 7 in Figure 1, and fixed thereto by means of a nut on the outer end of said mandrel, represented by dotted lines at 8, said nut clamping the cover plate 4 against the side edge of the casing. Preferably the cover plate 4 is grooved, as at 9, and the side edge of the casing 1 is beveled, as at 10, for interfitting relation to form a dust-proof seal between said plate and casing.

Extending inwardly from the closed side 2 of

said casing 1 is a plurality of pivot studs 11 disposed parallel with the axis of the casing and arranged in equidistantly spaced apart relation in a circular series, concentric to said axis, said studs being contiguous to the inner circumferential wall of the casing and terminating short of the cover plate 4. The studs 11 have reduced inner ends, as at 12, extended through the closed side 2 of the casing 1 and upset, as at 13, to anchor the same to said side. 10

A plurality of cylindrical roll holders 14 are pivotally mounted at one side thereof on said studs 11, respectively, parallel axially with said studs and for outward swinging movement in said casing 1 under the action of centrifugal force, said holders trailing the studs under rotation of the casing 1 in one direction, i. e., clockwise as indicated by the arrows in Figure 1. Preferably, for mounting the holders 14 on the studs 11, each holder is provided with an exterior radial boss 15, extending along one side thereof and apertured, as at 16, to fit over the related stud 11. The holders 14 are each diametrically split to provide, in what constitutes the outer side thereof, a narrow longitudinally extending slot 17. 20

The casing 1 is provided in the circumferential wall thereof with a plurality of transversely extending equidistantly spaced slots 18 extending from the closed side 2 parallel with the axis 30 of the casing and opening onto the side edge of the casing at the open side of the latter. There are the same number of slots 18 as there are holders 14 and said slots 18 are arranged in said casing in circumferentially offset, rearward relation to the slots 17 of the holders 14, as regards the direction of rotation of the casing 1, so that the slots 18 trail the slots 17 under rotation of said casing in the direction indicated and for a purpose presently seen. 35

In the use and operation of the invention, the cover plate 4 being temporarily removed, the holders 14 are loaded with rolls, as at 19, of flexible, abrasive material, paper, or cloth, and the outer ends 20 of said rolls are extended out of the casing 1 by way of the slots 17 of the holders 14 and the slots 18 in the casing 1 to provide free flaps, as at 21, said flaps being passed from the holders 14 through the adjacent slots 18 in the casing. Under rotation of the casing 1 the holders 14 are thrown outwardly on the studs 11 whereby the flaps 21 are flexed, or bent, by the sides of the slots 17, as at 22, and frictionally gripped by the edges of the slots 17 in a manner such that a friction lock is formed between the 50 55

holders and flaps preventing the rolls 19 from paying off the abrasive material and thereby maintaining selected lengths of flaps. As the holders 14 move outwardly, the flaps 21 are similarly gripped by the sides of the slots 18 thereby forming a friction lock between the flaps and the casing 1 as will be clear. When the cylinder 1 is stationary, the flaps 21 may be torn off and replaced by other lengths pulled from the rolls 19, the holders 14 swinging under the pull exerted on the material to break the friction locks described and permit the material to be easily pulled from the rolls 19.

The flaps 21 may be used to whip an article being sanded, or, backed by the casing as will be understood.

The foregoing will, it is believed, suffice to impart a clear understanding of the invention without further explanation.

Manifestly the invention, as described, is susceptible of modification without departing from the inventive concept and right is herein reserved to such modifications as fall within the scope of the subjoined claims.

What we claim is:

1. A centrifugal sanding head for rotation by a mandrel comprising a cylindrical casing having open and closed sides, respectively, and a plurality of transversely extending slots therein equidistantly spaced apart circumferentially thereof, a disk-like cover plate for the open side of the casing, said plate and the closed side of the casing being axially bored for mounting on said mandrel and a plurality of cylindrical roll holders for rolls of abrasive sheet material corresponding in number to said slots and pivotally mounted in said casing parallel with said slots in opposed relation to the same, respectively, said holders being slotted longitudinally, respec-

tively, opposite the slots of said casing for the extension of said sheet material from the holders through the slots thereof and the opposed slots in the casing to form free abrasive flaps outside said casing, said holders being swingable outwardly on the pivots thereof under the action of centrifugal force whereby said material is pulled taut against the side edges of the slots to frictionally lock the same to said holders and casing.

2. A centrifugal sanding head for rotation by a mandrel comprising a cylindrical casing having open and closed sides, respectively, and a plurality of transversely extending slots therein equidistantly spaced apart circumferentially thereof, a disk-like cover plate for the open side of the casing, said plate and the closed side of the casing being axially bored for mounting on said mandrel, and a plurality of cylindrical roll holders for rolls of abrasive sheet material corresponding in number to said slots and pivotally mounted in said casing parallel with said slots in opposed relation to the same, respectively, said holders being slotted longitudinally, respectively, opposite the slots of said casing for the extension of said sheet material from the holders through the slots thereof and the opposed slots in the casing to form free abrasive flaps outside said casing, said holders being swingable outwardly on the pivots thereof under the action of centrifugal force whereby said material is pulled taut against the side edges of the slots to frictionally lock the same to said holders and casing, and said holders being staggered circumferentially relative to the slots in the casing to facilitate frictionally locking the material to said side edges of the slots.

H. CLYDE HALL.
